UNITED STATES PATENT OFFICE.

ALFRED B. SABIN, OF LARAMIE, WYOMING.

STROKE-REGULATOR FOR WINDMILLS.

1,378,621.

Specification of Letters Patent. Patented May 17, 1921.

Application filed June 21, 1920. Serial No. 390,430.

To all whom it may concern:

Be it known that I, ALFRED B. SABIN, a citizen of the United States, residing in the city of Laramie, Albany county and State of Wyoming, have invented new and useful Improvements in Stroke-Regulators for Windmills, of which the following is a specification.

This invention relates to a stroke-regulator for adjusting the stroke of a pump or any other device actuated by a reciprocating movement. While the invention may be used in connection with different kinds of machinery, it is described in the following specification as applied to a wind mill. The general object of the invention is to provide a very simple and compact regulator which will operate automatically to adjust the crank arm to which the connecting rod is attached that operates the pump. A special object of the invention has been to produce a construction in which the crank pin will be securely held in any of its adjusted positions and without the presence of any lost motion; and also to construct the device in such a way that the adjusting mechanism is a "locked mechanism" as regards the crank pin, so that the crank pin can exert its force on the connecting rod without being moved in the slightest degree from its path of movement by the forces developed in the connecting rod; also to construct the crank arm in a simple manner which will facilitate the mounting of the parts of the mechanism within it.

Further objects of the invention will appear hereinafter.

The invention consists in the novel features, and in the general combination of parts to be particularly described herein-after, all of which contribute to produce a simple and efficient stroke-regulator for windmills. A preferred embodiment of my invention will be described in the following specification, while the broad scope of my invention will be pointed out in the appended claims.

In the drawing,

Figure 1 is a rear elevation of a windmill mechanism showing the central portion of the wind wheel, certain parts of the mechanism being broken away;

Fig. 2 is a vertical cross section through the arm at the middle point; the view shows the hub of the auxiliary wind wheel in section;

Fig. 3 is a plan of the arm with the outer section or cover of the arm removed;

Fig. 4 is a cross section through the hub of the auxiliary wheel and illustrating the manner in which a spring is mounted therein; and

Fig. 5 is a section taken on the line 5—5 of Fig. 3 but showing the bolt in place instead of removed as in Fig. 3.

Referring more particularly to the parts, 1 represents the shaft of the main wind wheel, the central portion of which is indicated by the dotted lines at 2. This shaft 1 is rotatably mounted in a suitable bearing 3 which has a downward extension 4 which may be mounted to swivel in a bearing in any suitable manner to enable the wind wheel 2 to be held in a plane substantially at right angles to the direction of the wind. One end of the shaft 1 carries a circular head 5 to which there is attached a crank arm 6 and this crank arm is preferably constructed of two sections 6^a and 6^b which are clamped together and secured to the head 5 by long through bolts 7 (see Fig. 2) and short through bolts 8 (see Figs. 1 and 5). On this arm 6 there is guided a crank pin 9 with which there is associated threaded adjusting means 10. This threaded adjusting means is actuated by an auxiliary wind wheel 11 (see Fig. 2) which is mounted on the end of the shaft 1. The auxiliary wheel 11 is preferably formed with a hollow hub 12 which is connected to the shaft 1 by means of a spiral spring 13. It should be understood that the auxiliary wheel is in front of the main wind wheel so that the wind comes against it in the direction of the arrows indicated in Fig. 2. The effect of the wind is to rotate the auxiliary wind wheel in the same direction as the main wind wheel. The spring 13 is mounted in such a way that if an acceleration of rotation of the auxiliary wheel takes place, the tension in the spring 13 will be increased; in other words, if the wind becomes stronger there will be a relative angular advance of the auxiliary wheel 11 with respect to the main wind wheel.

This relative movement is utilized by means of an inner shaft 14 which is rigidly secured to the hub 12 and which lies within the main shaft 1 which is made of tubular form. Any suitable means is provided for connecting the inner shaft 14 with the ad-

justing means 10 to utilize this relative movement, the operation being such that when the wind velocity increases the adjusting means 10 will be actuated in a manner 5 to move the crank pin 9 further away from the shaft 1. This will increase the stroke of the pump, the plunger of which is actuated by a connecting rod 15 attached to the crank pin, (see Fig. 1).

10 In order to accomplish these effects I prefer to construct the two sections 6^a and 6^b of the arm with coöperating recesses which come together to form an internal guideway 16 for guiding the crank pin 9. The 15 crank pin 9 is preferably mounted on a cross head or block 17 which slides along this guideway. The sections 6^a and 6^b are also provided with recesses of semicircular form which coöperate to form circular 20 pockets 18 and in each of these pockets there is mounted a worm wheel 19. These worm wheels 19 coöperate with a pair of adjusting screws 20 so as to effect a movement of the cross head 17. In the present instance these 25 worm wheels are constructed so that they operate as nuts on the threads of the two feed screws or adjusting screws 20. For convenience the hubs of these worm wheels are mounted in suitable ball bearing collars 30 21 which are received in sockets 22 formed in the adjacent faces of the two arm sections 6^a and 6^b, and the sides of these collars 21 may be provided with dowel screws 24 which assist in securing the collars in place. 35 The screws 20 extend beyond the collars 21 and are secured to a cross head in the form of a yoke 25 (see Fig. 3). On the shaft 14 between the two worm wheels 19 a worm 40 26 is mounted. This worm meshes with both of the worm wheels (see Fig. 2) and rotates them in opposite directions. With this construction it will be evident that an increase of wind velocity will cause an outward adjusting movement of the crank pin 9 and a 45 reduction of wind velocity will cause an inward movement of the crank pin 9 on the crank arm 6; in this way the stroke of the pump will be automatically changed or regulated to adapt it to the power being 50 developed by the main wind wheel.

The crank pin 9 projects through a slot 27 in the outer wall of the outer arm section 6^b and in order to protect the interior of the crank arm from the weather this slot 55 is closed, or substantially closed by a slide in the form of a plate 28, the edges of which slide along under parallel cleats 29.

In order to provide a clearance for the connecting rod 15, the outer ends of the 60 bolts 7 are countersunk into the wall of the casing. The special bolts 8 are also countersunk into the wall of the arm section 6^a in order to prevent their interfering with the free movement of the cross heads 17 and 25.

65 It is understood that the embodiment of

the invention described herein is only one of the many embodiments my invention may take, and I do not wish to be limited in the practice of my invention nor in my claims, to the particular embodiment set forth.

70

What I claim is:

1. In an automatic stroke-regulator for a windmill, the combination of a shaft for the main wind wheel, a crank arm carried by the shaft, a crank pin guided in said crank arm and adapted to be attached to the connecting rod that actuates the pump, threaded adjusting means mounted in the crank arm for moving the crank pin in or out on the arm, an auxiliary wind wheel rotatably mounted on the axis of the shaft, a spring connecting the same with the shaft and mounted so that its tension will be increased by an accelerated rotation of the auxiliary wheel, and means actuated by the auxiliary wheel and coöperating with the threaded means for automatically adjusting the crank pin on the arm.

75

2. In an automatic stroke-regulator for a windmill, the combination of a shaft for the main wind wheel, a crank arm carried by the shaft, a cross head carrying a crank pin and guided in the crank arm, said crank pin being adapted for attachment to a connecting rod to actuate a pump, threaded adjusting means mounted in the crank arm and connected with the cross head for moving the same in or out on the arm, an auxiliary wind wheel rotatably mounted on the axis 80

85

of the shaft, a spring connecting the same with the shaft and mounted so that the tension of the spring will be increased by an accelerated rotation of the auxiliary wheel, an inner shaft within the first named shaft 95 and connected with the auxiliary wheel so as to be rotated thereby, and means on the inner shaft coöperating with the threaded adjusting means for automatically adjusting the cross head on the arm.

90

3. In an automatic stroke-regulator for a windmill, the combination of a shaft for the main wind wheel, a crank arm carried by the shaft, a cross head carrying a crank pin and guided in the crank arm, said crank pin being adapted for attachment to a connecting rod to actuate a pump, a pair of feed screws mounted in the crank arm and connected with the cross head for moving the same in or out on the arm, an auxiliary wind wheel rotatably mounted on the axis of the shaft, a spring connecting the same with the shaft, and mounted so that the tension of the spring will be increased by an accelerated rotation of the auxiliary wheel, an inner shaft within the first named shaft 100 and connected with the auxiliary wheel so as to be rotated thereby, and means carried by the inner shaft, coöperating with the said feed screws for automatically adjusting the cross head on the arm.

105

110

115

120

125

130

4. In an automatic stroke-regulator for a windmill, the combination of a shaft for the main wind wheel, a crank arm carried by the shaft, a cross head carrying a crank pin 5 and guided in the crank arm, said crank pin being adapted for attachment to a connecting rod to actuate a pump, a pair of feed screws rigidly attached to the cross head, a nut corresponding to each feed screw and 10 rotatably mounted in the arm, each of said nuts being in the form of a worm wheel, a worm disposed between and engaging both of the worm wheels to rotate the same, an inner shaft within the first named shaft and 15 carrying the said worm, an auxiliary wind wheel rigid with the inner shaft, and a spring connecting the auxiliary wind wheel with the first named shaft and mounted so that the tension of the spring will be increased by an accelerated rotation of the 20 wind wheel.

5. In an automatic stroke-regulator for a wind mill, the combination of a shaft for the main wind wheel, a crank arm carried by the shaft and consisting of two sections clamped together and coöperating to form a substantially rectangular guideway therebetween, a pair of feed screws mounted in the guideway, a cross head movable along the guideway, attached to the two feed screws, and carrying a crank pin adapted to be attached to a connecting rod that actuates a pump, said crank arm sections having recesses in 25 their adjacent faces coöperating to form two 30 pockets, a worm wheel in each of said pockets operating as a nut on its corresponding feed screw, a worm wheel held between the 35

two arm-sections and meshing with the worm wheels to rotate the same, an inner shaft carrying the worm wheel and disposed within the first named shaft, an auxiliary wind wheel carried by the inner shaft, and a spring connecting the auxiliary wheel with the first named shaft and mounted so that its tension will be increased by an accelerated 40 45 rotation of the auxiliary wheel.

6. In an automatic stroke-regulator for a windmill, the combination of a shaft for the main wind wheel, a crank arm carried by the shaft and consisting of two sections 50 clamped together and coöperating to form a substantially rectangular guideway therebetween, threaded adjusting means mounted in the guideway, a cross head movable along the guideway by the adjusting means, one 55 of said sections having a slot therein, a crank pin carried by the cross head extending through the slot and adapted to be attached to a connecting rod for actuating a pump, a slide guided on the exterior of the crank 60 arm for covering the said slot, an auxiliary wind wheel, a spring connecting the same with the first named shaft and mounted so that the tension therein will be increased by an acceleration of rotation of the auxiliary 65 wheel, an inner shaft within the first named shaft and carrying the auxiliary wheel, and means actuated by the inner shaft and co-operating with the adjusting means to adjust the cross head in or out on the arm. 70

In testimony whereof, I have hereunto set my hand.

ALFRED B. SABIN.
